UNITED STATES PATENT OFFICE.

EDWARD E. PETTEE AND JOHN J. McCUTCHAN, OF NEW YORK, N. Y., AS
SIGNORS, BY MESNE ASSIGNMENTS, TO THE AUTOMATIC AIR CARRIAGE
COMPANY, OF NEW YORK.

COMPRESSION OF AIR AND UTILIZATION THEREOF.

SPECIFICATION forming part of Letters Patent No. 637,659, dated November 21, 1899.

Application filed March 9, 1899. Serial No. 708,421. (No specimens.)

To all whom it may concern:

Be it known that we, EDWARD E. PETTEE and JOHN J. McCUTCHAN, citizens of the United States, and residents of the city of New York, county of New York, State of New York, have invented certain new and useful Improvements in the Compression of Air and Utilization Thereof; and we do hereby declare the following to be a full, clear, and exact description of the invention, such as will enable others skilled in the art to which it appertains to make and use the same.

Our invention relates to certain new and useful improvements in the compression of air and the utilization of the compressed air for motive purposes.

The main characteristic feature of our invention consists in utilizing in the motor-cylinder the heat of compression developed in the air-compressor. In practice we realize this result by discharging the condensed air as soon as compressed directly from the compressor into the adjacent motor by a short connecting-pipe, which pipe is jacketed by the exhaust-pipe from the explosive-engine which operates the compressor, the arrangement being such that the products of combustion from the explosive-engine at a considerably higher temperature than that of the compressed air traverse the jacket surrounding the compressed-air-conducting pipe throughout the entire length of said pipe and preferably pass through an annular passage or jacket exterior to the working cylinder of the motor, finally passing out through the motor-cylinder exhaust.

A further important feature of our invention consists in supplying the compressor with moist warm air, the air receiving its moisture at atmospheric pressure, at which pressure its capacity for holding moisture in suspension is greater than at any higher pressure or greater density at any given temperature. For the purpose of simultaneously warming and moistening the air-supply of the compressor we preferably bring it into contact with the water employed for supplying the water-jacket for the explosive-engine, whereby the air itself is made available for abstracting heat from

the water and keeping it at the desired moderate temperature. 50

In the accompanying drawings, Figure 1 represents in plan view, partly in section, an arrangement of parts embodying our invention. Fig. 2 represents in central vertical section the compressor and the explosive-engine for operating the same. Fig. 3 represents a central section through the air-motor. Fig. 4 represents a cross-section through the air preheating and moistening tank. 60

Similar letters of reference indicate similar parts throughout the several views.

Referring to the drawings, A represents the cylinder of the explosive-engine, and A' the piston thereof, said piston being connected by the oscillatory rod B with the crank-shaft C. The piston D of the air-compressing cylinder E is connected to the crank-shaft C at an angle of one hundred and eighty degrees to the crank connection of the engine-cylinder by means 70 of the rod B'.

Upon the outer end of the crank-shaft C is mounted the balance-wheel F, fixed to the shaft, as is also the gear F', which gear meshes with the gear F², fixed to the cam-shaft F³ and of twice the diameter of the gear F'. Upon the cam-shaft F³ are fixed the cams a² a³ a⁴, which are adapted to actuate the corresponding rods a⁵ a⁶ a⁷, said rods being provided with springs, as shown, for maintaining their lower ends in contact with the surfaces of the cams. To the rod a⁵ is attached the valve b², which governs the inlet to the explosive-engine. To the rod a⁷ is attached the valve b³, which governs the exhaust of the explosive-engine, and the rod a⁶ terminates as a contact for closing an electric circuit through the conductors b⁴ b⁵. As the rod a⁶ rises it makes electric connection with the insulated contact b⁶, so that when the rod a⁶ is withdrawn from the insulated contact an electric spark is formed to explode the mixture of gas and air or oil-vapor and air within the space G. The explosion of the mixture causes the piston A' to descend and drives the air-compressor piston D upwardly, thereby compressing the air in front of the piston D and causing it to pass through the exhaust-valve c² 95

into the conducting-pipe H. The air-compressor cylinder is provided with an inlet-valve c⁸, which opens and permits the entrance of air into the cylinder E on the down-
ward stroke of the piston D.

To start the explosive-engine, the balance-wheel F is turned one revolution until the piston A' has descended within its cylinder and drawn air and gas or air and oil-vapor in their proper proportions through the valve b², which has been opened by the cam a² as the piston descended. When the piston reaches the downward limit of its stroke, the cam a² releases the rod a⁵ and the valve b² closes. As the piston A' rises the mixture of air and gas is compressed within the space G, and at the same time the cam a³ raises the rod a⁶, causing it to make contact with the insulated contact b⁶. When the piston A' has reached the upper limit of its stroke, the balance-wheel F carries the shaft C somewhat past the center and the cam a³ releases the rod a⁶, which immediately drops and breaks the circuit, thereby causing an electric spark, which explodes the mixture of gas and air and forces the piston A' down within its cylinder, thereby revolving the shaft C and operating the compressing-piston D. As piston A' returns to its upper position the cam a⁴ raises the rod a⁷ and opens the valve b³, thereby allowing the exploded gases to pass into the exhaust. When the piston A' has reached the limit of its upstroke, the cam a⁴ lets go of the rod a⁷, whereupon said rod drops and closes the valve b³. At the same time the valve b² opens and a new supply of gas and air is drawn into the cylinder, as hereinbefore described.

To supply the explosive-engine with fuel, we may conveniently employ a storage-receptacle L, containing either oil or compressed gas, and to extract the heat from the walls of the expansion-cylinder to a suitable degree we provide an annular space c⁴, within which water may circulate from the water-reservoir M. From the space c⁴ for this purpose pipes f² f³ lead into the water-reservoir M and terminate below the level of the water therein, the water-level in the reservoir M being of such height as to leave a free space above the same, through which the air for supplying the compression-cylinder may be drawn. To this end the water-reservoir is provided with an air-inlet f⁴, so that the air entering at f⁴ shall pass through and in contact with the water in the receptacle M and finally through the pipe f⁵ to the air-compressor cylinder.

The pipe H leads directly to the distributing-chamber N of the motor and is jacketed throughout its entire length by the exhaust-

conduit N' of the explosive-engine, so that the heat developed by the compression of the air in the compression-cylinder shall be maintained by the hot products of combustion until the compressed air is delivered into the motor. The products of combustion enter the passage n², which surrounds the distributing-chamber N and the cylinder P of the motor, and finally pass out through the exhaust-port n³ of the motor, together with the expanded air from said cylinder. This latter feature is useful for preventing the formation of ice at the point of passage of the expanded air into the atmosphere, a difficulty frequently encountered, especially in cold weather, and which sometimes results in diminishing and choking the exhaust-air outlet and finally closing it, thereby stopping the motor.

The motor-cylinder is provided with a piston P', and the distributing-chest N is provided with a slide-valve N², the latter being operated by an eccentric or otherwise from the crank-shaft to which the piston is attached, as will be readily understood. A branch H' may be taken from the pipe H, if desired, to supply an auxilliary reservoir M', having a safety-valve m² and gage m³, said reservoir being adapted to receive a reserve or surplus quantity of compressed air to assist in the operation of the motor when for a limited time its requirements are greater than would be supplied by the normal output of the compressor-cylinder.

Having thus described our invention, what we claim is—

1. The method of compressing air and utilizing the same for motive purposes which consists in preheating and moistening the air and compressing it in that condition and maintaining the heat of compression of the dense moist air throughout its passage from the compressor to the motor; substantially as described.

2. The method of utilizing in a motor, the heat of compression developed in an air-compressor supplying said motor, which consists in maintaining the compressed air at the temperature developed in the air-compressor cylinder during its passage into the motor; substantially as described.

In testimony whereof we affix our signatures in presence of two witnesses.

EDWARD E. PETTEE.
JOHN J. McCUTCHAN.
